United States Patent Office

Des. 185,543
Patented June 23, 1959

185,543

WATER TESTING KIT

Gomer S. Frank, Reseda, and Hugh L. Fry, Sepulveda, Calif., assignors to Gomer S. Frank and Hugh L. Fry, a partnership of California, doing business as Industrial Specialties, Los Angeles, Calif.

Application March 4, 1957, Serial No. 45,092

Term of patent 7 years

(Cl. D16—2)

FIG. 1

FIG. 2

FIG. 3

FIG. 4

Figure 1 is a side elevational view of a water testing kit embodying our new design.

Figure 2 is an end elevational view as seen from the right of Figure 1.

Figure 3 is a top plan view thereof.

Figure 4 is an end elevational view as seen from the left of Figure 1.

The side not shown in the drawing is substantially the same as that shown in Figure 1.

We claim:

The ornamental design for a water testing kit, substantially as shown and described.
